UNITED STATES PATENT OFFICE

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA

CAR ROOF

Application filed June 27, 1931. Serial No. 547,327.

This invention relates to insulated car roofs of the type shown in my Patent No. 1,643,975, dated October 4, 1927, wherein the metal roof sheets are rigidly connected along their adjacent margins by upstanding seams that function as outside carlines and have stiffening plates embodied therein that constitute hangers for suspending the insulating lining from the roof.

10 The principal object of the present invention is to provide a simple and efficient arrangement for attaching the insulating lining to the roof that will increase the strength and rigidity of the roof. Other objects are 15 cheapness and compactness of construction and fewness of parts.

The invention consists principally in the means for suspending the insulating lining from the roof; and it also consists in the parts 20 and in the construction and arrangements of parts hereinafter described and claimed.

In the accompanying drawing, which forms a part of this specification and wherein like symbols refer to like parts wherever 25 they occur,

Fig. 1 is a plan view of a portion of an insulated car roof embodying my invention.

Fig. 2 is a vertical transverse section through one-half of the roof on the line 2—2 30 in Fig. 1.

Fig. 3 is a vertical cross-section through the roof at one of the seams 3—3 in Fig. 2; and

Fig. 4 is a section similar to Fig. 3, showing a modified construction.

The present roof comprises roof sheets 1 that extend from side plate 2 to side plate 2 of the car and slope downwardly on opposite sides of the ridge to form a pitch or arculate roof. The side plates 2 are preferably of Z-shaped cross-section with their webs disposed horizontally and with their inner flanges 3 extending upwardly. The roof sheets are preferably supported at the eaves 40 on the outstanding top flanges of angle-shaped eaves strips 4 which extend longitudinally of the car with their depending flanges riveted or otherwise rigidly secured to the outer faces of the upstanding inner flanges 3 of the side plates 2. The roof sheets are riveted or other-

wise rigidly secured to the outstanding top flanges of the eaves strips 4 and are preferably provided at their eaves ends with depending drip flanges 5 that overhang the outer edges of said eaves strips. The roof sheets are arranged on the car side by side and are provided along their adjacent margins with upstanding seam flanges 6 that are beveled or coped off at the eaves ends of the roof sheets. The body portions of the roof sheets are preferably offset upwardly adjacent to the upstanding seam flanges 6 to form raised panels 7 at the side margins of the sheets.

Metal seam caps 8 of substantially U-shaped cross-section are placed astride adjacent seam flanges 6 of adjacent roof sheets and are rigidly secured to said flanges by horizontal rivets 9, thereby forming upstanding seams that function as exterior carlines for the roof. The seam caps 8 extend from eaves to eaves of the car and are provided with outstanding base flanges 10 that rest on the raised side marginal panels 7 of adjacent roof sheets and are turned down at the eaves over the depending drip flanges 5 of said sheets. The seam caps 8 are preferably curved downwardly over the beveled or coped off eaves ends of the upstanding seam flanges 6 straddled thereby.

A running board 11 extends longitudinally of the car at the ridge and is supported on and secured to the lateral top flanges of angle-shaped running board saddles 12 that are secured to the sides of the seam caps 8 by the securing rivets 9 therefor.

Additional strength and rigidity are imparted to the upstanding seams by means of metal plates or strips 13 embodied therein. Each of these stiffening plates 13 is of substantially angle-shaped cross-section and has one flange disposed vertically and interposed between the adjacent upstanding roof sheet flanges 6. Each seam stiffening plate 13 preferably extends from the upstanding flange 3 of the side plate 2 to a point adjacent to the ridge and secured within the seam by means of the rivets 9 that secure the seam cap 8 to the adjacent side marginal seam flanges 6 of the roof sheets. The seam stiffening members or plates 13 are made deep enough

so that their laterally extending base flanges 14 are spaced far enough below the raised side marginal panel 7 of the roof sheet located thereabove to accommodate wooden 5 nailing strips 15. These nailing strips 15 are supported on the base flanges 14 of the seam stiffening plates 13 and are secured to the vertical flanges thereof by means of horizontal bolts 16 that pass through aligned openings provided therefor in said nailing strips and in the upstanding flanges of said stiffening plates. The wooden nailing strips 15 are made wider than the base flanges 14 of the 10 seam stiffening plates 13; and an insulating 15 lining 17 comprising boards or other suitable insulating material is nailed or otherwise secured to the undersides of the portions of said nailing strips located beyond the base flanges of said seam stiffening plates. As shown in 20 the drawing, the nailing strips 15 are rabbeted to fit the base flanges 14 of the seam stiffening plates 13, thereby bringing the bottoms of portions of the strips located beyond said base flanges flush with the bottoms thereof.

The hereinbefore described arrangement provides a simple and efficient means for attaching a lining to a car roof of the type hereinbefore described. It enables the depth of 30 the vertical flange of the seam stiffening plate to be increased and thus increases the load-carrying capacity of the seam without decreasing the headroom of the car; it eliminates the necessity for notching the base 35 flange of the seam stiffening plate and the necessity for rabbeting or grooving of the upper surface of the nailing strip; and it enables the nailing strip to be supported upon the base flange of the seam stiffening plate, 40 which nailing strip is firmly held in position by bolts that pass horizontally through said strip and the vertical flange of said plate.

In the modified construction as shown in 45 Fig. 4, the seam stiffening plate 13a is shown in the form of a plate without a lateral base flange; and the nailing strip 15a is secured to the side of said plate by means of a horizontal bolt 16a whose head portion is preferably riveted or otherwise rigidly secured to said plate so as to prevent said bolt from tilting vertically.

What I claim is:

1. In a car roof, a series of plates embodied 55 therein and extending transversely thereof, said plates extending below the underside of said roof, members located alongside of said plates, horizontal fasteners for securing said members to the sides of said plates, and a lining secured to the undersides of said members.

2. In a car roof, a series of plates embodied 60 therein and extending transversely thereof, said plates extending below the underside of said roof and being provided at their lower edges with laterally projecting flanges, mem-

bers resting on said flanges, means for securing said members to the sides of said plates, and a lining secured to said members.

3. In a car roof, a series of plates embodied 70 therein and extending transversely thereof, said plates extending below the underside of said roof and being provided at their lower edges with laterally projecting flanges, wooden members resting on said flanges, means for securing said members to the sides 75 of said plates, said members being wider than said flanges, and a lining secured to the portions of said members located beyond said flanges.

4. In a car roof, a series of plates embodied 80 therein and extending transversely thereof, said plates extending below the underside of said roof and being provided at their lower edges with laterally projecting flanges, wooden strips resting on said flanges with their upper surfaces in contact with the underside of said roof, and fastening members extending horizontally through said wooden strips and said plates for securing said strips to the sides 85 of said plates.

5. A car roof comprising roof sheets connected by upstanding seams, plates embodied in said seams and extending below said roof sheets, members located beneath said roof and secured flatwise against the sides of said plates, and a lining secured to said members.

6. A car roof comprising roof sheets connected by upstanding seams, plates embodied in said seams and extending below said roof sheets, wooden members located beneath said 100 roof and secured to the sides of said plates, and a lining secured to said members, said plates being provided with laterally extending flanges extending beneath said members for supporting the latter.

7. A car roof comprising roof sheets connected by upstanding seams, plates embodied in said seams and extending below said roof sheets, wooden members located beneath said 110 roof alongside of said plates, horizontal fastening members for securing said members to the sides of said plates, and a lining secured to the undersides of said members.

8. A car roof comprising roof sheets connected by upstanding seams, plates embodied in said seams and extending below said roof sheets, wooden members located beneath said roof alongside of said plates, horizontal fastening members for securing said members to the sides of said plates, said plates being 120 provided at their lower edges with laterally extending flanges of less width than said members for supporting said members, and a lining secured to the undersides of said members.

Signed at New Kensington, Pennsylvania, this 22nd day of June, 1931.

CHARLES DAVID BONSALL.
